Attorney.

UNITED STATES PATENT OFFICE.

HARRY C. STAGEMAN, OF COUNCIL BLUFFS, IOWA.

PHONOGRAPH SOUND-REGULATOR.

1,389,605.

Specification of Letters Patent. Patented Sept. 6, 1921.

Application filed March 15, 1920. Serial No. 365,881.

To all whom it may concern:

Be it known that I, HARRY C. STAGEMAN, a citizen of the United States, residing at Council Bluffs, county of Pottawattamie, and State of Iowa, have invented a new and useful Phonograph Sound-Regulator, of which the following is a specification.

My invention relates to improvements in phonograph sound regulators in which a clarifying chamber is employed with one or more intensifiers and the objects of my improvement are:

1. To soften the tones produced in the phonograph horn and successively intensify the same; 2. To produce such a device in which the parts are easily applied to the ordinary phonograph horn of whatever form.

I attain these objects by the structure in the accompanying drawing in which Figure 1 is a diagrammatic section of a phonograph horn showing sections of the clarifier and a succession of intensifiers; Fig. 2 is a side elevation of the clarifier, and Fig. 3, elevations respectively of the perforated diaphragms separating the chambers of the clarifier.

Similar letters refer to similar parts throughout the several views.

r represents a record resting upon the revolving table *t*, of the ordinary phonograph. The needle *n*, communicates with the reproducing head *f*, having the reproducing diaphragm *s*, attached to the reproducing head *f*, on the ordinary horn of the phonograph *h*.

The clarifier *c* consists of a succession of two or more chambers, *b*, *b'* and *b''*, divided from each other and from the anterior and posterior chambers of the horn by perforated diaphragms, *d*, *e*, *d'* and *e'*. These diaphragms are arranged with perforations which alternate in the clarifier so that the sound waves in the air space in each chamber *b*, *b'* and *b''* are more or less broken in each chamber. Fig. 3, illustrates the position of the perforations in the diaphragms *d* and *d'*, and Fig. 4, represents the relative position in the diaphragms *e* and *e'*. One of the diaphragms or ends of the clarifier *c* as *d*, is extended to form a support and fit the phonograph horn at suitable distance from the reproducing diaphragm *s*, of the phonograph.

My invention relates to instrumentalities applied to the ordinary phonograph to produce sound regulations for first clarifying

and then intensifying the sounds produced by the ordinary phonograph.

The intensifier consists of a supporting perforated head *g* or *g'*. Attached to the perforated head *g* or *g'* is a suspended diaphragm *i* or *i'*, and attached to the diaphragm *i* or *i'* is a spring *n*' or *n''* upon which is suspended or to which is attached a suitable auxiliary horn *k* or *k'*, which does not touch any part of the phonograph, except as it is connected by the spring *n*' or *n''* with the supporting perforated head *g* or *g'*.

One or more of the intensifiers may be used as desirable to produce the proper tone. Preferably I use two. The auxiliary horn *k* or *k'* is formed by a diaphragm *l* or *l'* attached by a soft ring or substance *m* or *m'*, to a horn or funnel shaped piece.

I have found by inserting these chambers of the clarifiers in the passage of the horn so that the waves of sound pass through the chambers of the clarifier *c*, as *b*, *b'* and *b''*, with some of the perforations of the diaphragm thereof, *d*, *e*, *d'*, *e'*, staggered or placed alternately with each other, a very softening effect is produced upon the sounds reproduced by the record. By placing in the horn a perforated diaphragm as *g*, with a sounding diaphragm *i*, attached by a spring connection to a second diaphragm *l*, of an auxiliary horn *k*, I have found that it greatly softens and intensifies the desired tones of the phonograph.

By the use of the clarifier and one or more intensifiers the scratch and squeak sound of a needle on the record is eliminated and the finer and more perfect tone of the desired sound is preserved.

What I claim is:

1. The combination with a phonograph horn of a sound modifier comprising a perforated head, a centrally supported diaphragm, an auxiliary horn and a spring forming a resilient connection between the auxiliary horn and the head.

2. The combination with a phonograph horn of a sound modifier comprising a perforated head, a sound diaphragm arranged at one side of the perforated head, an auxiliary horn located at the opposite side of the perforated head and a spring connection between the head and the diaphragm and the auxiliary horn.

3. The combination with a phonograph horn, of a plurality of sound modifiers in-

2
serted in the phonograph horn and successively increasing in size with the increasing diameter of the horn, said modifiers being provided with a centrally suspending diaphragm and having a yieldably mounted oscillatory horn provided with a dia-

phragm.

4. The combination with a phonograph horn, of a clarifier comprising a cylindrical body spaced from the walls of the horn

and provided with a plurality of transverse partitions having apertures arranged in staggered relation, and a flanged head embracing one end of the said body and fitting the interior of the horn and provided with 15 apertures.

HARRY C. STAGEMAN.
